his Attorney.

UNITED STATES PATENT OFFICE

LE ROY A. DROESCHER, OF WILLOW GROVE, PENNSYLVANIA, ASSIGNOR TO C. H. WHEELER MANUFACTURING COMPANY, OF PHILADELPHIA, PENNSYLVANIA, A CORPORATION OF PENNSYLVANIA

REFRIGERATING APPARATUS

Application filed February 27, 1931. Serial No. 518,679.

My invention relates to refrigerating apparatus, and more particularly to that type in which water or other material is cooled or frozen in cans or receptacles immersed in a cooling medium.

In accordance with my invention the receptacle for the water or other material to be cooled or frozen, and herein for brevity styled a can, is provided on its exterior with fins or strips, in contact with the cooling medium, and in good heat conducting relation with respect to the walls of the can.

More particularly in accordance with my invention the can is disposed within and spaced from an outer casing in which the fins or strips are so disposed as to form a plurality of multiple passages through which the cooling medium passes in definitely defined paths for definitely controlling circulation of the cooling medium with respect to the can, for increasing the velocity of the cooling medium with respect to the can, and in general for accelerating the absorption of heat from the can into the cooling medium.

Further in accordance with my invention the casing falls short of the upper end of the can; and the can falls short of the lower end of the casing which latter is associated with further structure for defining a compartment communicating with the circulating system for the cooling medium.

My invention resides in structure of the character hereinafter described and claimed.

For an understanding of my invention, and for an illustration of some of the forms it may take, reference is to be had to the accompanying drawing, in which:

Fig. 1 is a perspective view, partly cut away, of can structure embodying my invention;

Fig. 2 is a vertical sectional view, partly in elevation, of can structure generally similar to that shown in Fig. 1, in association with means for effecting communication with the circulating system for the cooling medium;

Fig. 3 is a side elevational view, partly in vertical section, showing the can structure as disposed in a tank through which cooling medium is passed;

Fig. 4 is a side elevational view, partly in

section of a modified form of can structure;

Fig. 5 is a horizontal sectional view on the line 5—5 of Fig. 4.

Referring to Fig. 1, a can C of rectangular form, or any other suitable form including circular or cylindrical, as indicated in Figs. 4 and 5, comprises the wall 1 of sheet metal or other suitable material of high heat conductivity.

Welded, soldered, riveted or otherwise secured in good heat conducting relation with the outer sides of the wall 1 are the fins or strips 2, preferably of sheet metal or other material of high heat conductivity. The fins or strips 2 are suitably spaced from each other and are preferably disposed entirely around the can C.

Surrounding and spaced from the can C is the casing or housing K of any suitable material, preferably sheet metal. The fins or strips 2 are preferably attached at several convenient points to the inside of the casing K in any suitable way, as by welding, soldering or the like.

In my preferred arrangement the can C, fins or strips 2 and the outer casing K constitute a unitary can structure.

The can is provided with a bottom of any suitable structure. In the examples illustrated in Figs. 1 and 2, the bottom B is countersunk or dished, its downwardly extending flanges 3 extending to or adjacent the bottom of the can C.

The can terminates short of the lower end of the housing or casing K, as indicated in Figs. 1 and 2, so that between the bottom B of the can and other suitable structure there may be formed a compartment through which the cooling medium is passed to or from the spaces between the fins or strips 2. In the examples illustrated in Figs. 1 and 2 the lower end of the casing K rests in a groove in the sealing member D of wood or other material resting upon or set into the bottom A of a tank in which the cans are disposed and to and from which flows the cooling medium such as cold brine, as indicated in Fig. 3. The bottom of the casing K, the can bottom B, the sealing member D and the tank bottom A form a compartment E.

10 15 20 25 30 35 40 45 50 55 60 65 70 75 80 85 90 95 100

communicating with the numerous vertical passages defined by the fins or strips 2 and the walls of the can C and casing K. In the example illustrated cooling medium of suitably low temperature is introduced into the chamber or compartment E through the pipe 4.

As indicated in Fig. 3, the pipes 4 for the several cans communicate with a suitable manifold 5 into which the cooling medium from a suitable source is delivered, passing thence through the pipes 4 into the compartments E upwardly through the multiple passages defined by the fins 2 and the walls of the can and casing, to the top edge of the casing K where it overflows short of the top of the can C into the tank T which with its bottom A may be constructed of any suitable material, for example concrete, as indicated. Within the concrete may be embedded suitable metallic structure 6 itself forming, if desired, a closed sheet metal tank embedded in concrete or the like. Within the tank T is disposed a wall or weir 7 which extends substantially to the same height as the casings K for maintaining within the compartment in which the several cans C are disposed a full height of cooling medium notwithstanding irregularity in rate of withdrawal of cooling medium through the outlet pipe 8 opening into the compartment at the right of the weir 7 and preferably at a point substantially below the top of the weir.

Figs. 4 and 5 indicate that the can and its casing may be of any other suitable shape; in this example, circular or cylindrical.

In Fig. 4 the casing K is itself provided with a bottom 9, spaced below the lower ends of the fins 2 and the bottom of the can C to form the compartment E communicating with the pipe 4 for supplying cooling medium. In this instance, the upper end of the pipe 4 may terminate in a tapered portion upon which fits a tapered opening in the casing bottom 9. Upon the bottom 9 or the pipe 4 may be provided a member 10, reinforcing the structure at and adjacent the pipe 4.

Can structure of the character illustrated in Fig. 4 it will be understood may be used in the brine tank in lieu of those specifically indicated in Fig. 3.

By my structure the fins serve more rapidly to conduct heat from the can to the cooling medium. The multiple passages between the fins serve also to increase the velocity of the cooling medium over the surface from which it is to absorb heat and at the same time serve definitely to control the circulation of the cooling medium and in general accelerate the transfer of heat into the cooling medium.

The advantages of can structure in accordance with my invention are evident when compared with the common practice of circulating brine or cooling medium in a tank in which are disposed rows of cans or freezing

receptacles, which system is characterized by stagnation or slow movement of a large portion of the cooling medium outside of the more direct path or paths of circulation, resulting in low efficiency. In accordance with my invention, however, the cooling medium is definitely controlled; the entire periphery of the can is operating at substantially uniform and high efficiency in effecting heat transfer to the cooling medium. The fins or strips, with their metallic bond to the can proper, not only increase the area through which heat transfer may be effected, but define passages for the cooling medium resulting in higher overall efficiency of the refrigerating or ice making system.

Structure of the character herein disclosed may be utilized with any suitable system for circulating the brine or cooling medium, and for adequately lowering its temperature to produce the degree of refrigeration desired, such as the freezing of water into artificial ice. A suitable system for providing, circulating and lowering the temperature of the cooling medium is disclosed in my copending application Serial No. 521,414, filed March 10, 1931.

Each receptacle unit, comprising a can with its casing and appurtenances, is individually removable and replaceable, and has a detachable connection with the source of cooling medium.

What I claim is:

1. A receptacle for material to be refrigerated comprising a can, a casing surrounding and spaced therefrom, and fins disposed within the space between said can and casing defining multiply connected passages for the cooling medium, said casing extending below the bottom of said can to form a wall of a compartment for cooling medium communicating with said passages.

2. A receptacle for material to be refrigerated comprising a can, a casing surrounding and spaced therefrom, and fins disposed within the space between said can and casing defining multiply connected passages for the cooling medium, said casing extending below the bottom of said can, means for closing off the bottom of said casing to form a compartment with which said passages communicate, and a cooling medium connection with said compartment.

3. A receptacle for material to be refrigerated comprising a can, a casing surrounding and spaced therefrom, and fins disposed within the space between said can and casing defining multiple passages for the cooling medium, said casing extending below the bottom of said can, and itself open at its lower end, a member forming a joint between the lower end of said casing and the wall of a tank to form below the bottom of the can a compartment communicating with said passages, and

a fluid medium connection with said compartment.

4. A receptacle for material to be refrigerated comprising a can, a casing surrounding and spaced therefrom, and fins disposed within the space between said can and casing defining multiple passages for the cooling medium, said casing having a bottom spaced from the bottom of said can to form a compartment communicating with said passages, and a cooling medium connection with said compartment.

5. A receptacle for material to be refrigerated comprising a can, a casing surrounding and spaced therefrom, and fins disposed within the space between said can and casing defining multiple passages for the cooling medium, said casing terminating short of the top of said can, said casing extending below the bottom of said can to form a wall of a compartment for cooling medium communicating with each of said passages.

6. A receptacle for material to be refrigerated comprising a can, a casing surrounding and spaced therefrom, and fins disposed within the space between said can and casing defining multiple passages for the cooling medium, said casing and fins terminating short of the top of said can, said casing extending below the bottom of said can, and means extending across the lower end of said casing to define a compartment for cooling medium communicating with each of said passages.

7. The combination with a tank for refrigerating medium, of a plurality of refrigerating receptacles disposed therein, a source of supply of refrigerating medium, each of said receptacles having a casing within which it is disposed, and fins disposed within the space between the receptacle and casing defining multiply connected passages for the cooling medium, and connections from said source of supply to said casings individually for applying to said receptacles multiple streams of cooling medium overflowing the tops of said casings into said tank.

8. The combination with a tank for refrigerating medium, of a plurality of refrigerating receptacles disposed therein, a source of supply of refrigerating medium, each of said receptacles having a casing within which it is disposed, and fins disposed within the space between the receptacle and casing defining multiply connected passages for the cooling medium, connections from said source of supply to said casings individually for applying to said receptacles multiple streams of cooling medium overflowing the tops of said casings into said tank, a weir in said tank extending substantially to the height of said casings, and an outlet for the refrigerating medium on the side of said weir opposite to said receptacles.

9. The combination with a refrigerating can, of fin structure on the exterior thereof

forming multiple passages for the refrigerating medium, a compartment with which said passages respectively communicate, and means connecting said compartment with a source of supply of refrigerating medium.

10. In combination with a receptacle for material to be refrigerated comprising a can, a casing surrounding and spaced therefrom, fins disposed within the space between said can and casing defining multiple passages for the refrigerating medium, a compartment with which said passages respectively communicate, and means connecting said compartment with a source of supply of refrigerating medium.

11. In combination with a receptacle for material to be refrigerated comprising a can, a casing surrounding and spaced therefrom, fins disposed within the space between said can and casing defining multiple passages for the refrigerating medium, said casing terminating short of the top of said can, and inlet structure adjacent the bottom of the can connecting said passages with a source of supply of refrigerating medium.

12. In combination with a receptacle for material to be refrigerated comprising a can, a casing surrounding and spaced therefrom, fins disposed within the space between said can and casing defining multiple passages for the refrigerating medium, said casing terminating short of the top of said can, inlet structure adjacent the bottom of the can connecting said passages with a source of supply of refrigerating medium, and means for causing the refrigerating medium to flow upwardly through said passages and to overflow at the upper edge of said casing.

13. A receptacle for material to be refrigerated comprising a can, a casing surrounding and spaced therefrom, and fins disposed within the space between said can and casing defining multiple passages for the refrigerating medium, said casing and fins terminating short of the top of said can, said casing having a portion extending below the bottom of the can for connecting said passages with a source of supply of refrigerating medium.
